UNITED STATES PATENT OFFICE

GEORGE A. McCLAY, OF CHICAGO, ILLINOIS

PIPE FOR SMOKING TOBACCO

Application filed February 24, 1932. Serial No. 594,835.

This invention relates to pipes for smoking tobacco, it more particularly relating to an improved stem for such pipes.

One of the objects of the invention is to provide a stem for a smoker's pipe so constructed as to effectively drain nicotine-laden moisture from the draft passage of the stem at points between the shank of the bowl of the pipe and the mouth piece of the stem.

A further object of the invention is to provide means whereby the stem may be readily separated for cleaning purposes and as readily re-assembled.

15 A further object of the invention is to provide the stem with a chamber into which the nicotine-laden moisture from the draft passage of the stem may drain so constructed as to trap the moisture therein and prevent it from flowing back into the draft passage in the event the pipe is laid on its side, up-side-down, or with its bowl end down, and to also prevent the moisture from flowing into the socket of the shank of the 25 bowl.

Another object of the invention is to provide a stem for a smoker's pipe formed of separable sections which may be effectively locked together when in use and readily separated when it is desired to clean the stem.

Other objects of the invention will appear from the accompanying description.

In the accompanying drawing:

35 Fig. 1 is a top plan view of a pipe embodying my improvements.

Fig. 2 is a longitudinal section of the same.

Fig. 3 is a section on the line 3-3 of 40 Fig. 2.

Fig. 4 is a section on the line 4-4 of Fig. 2.

Fig. 5 is a section on the line 5-5 of Fig. 2.

45 Fig. 6 is a perspective view of the outer side of the upper section of the stem.

Fig. 7 is a perspective view showing the inner side of the upper section of the stem.

Fig. 8 is a perspective view showing the 50 inner side of the lower section of the stem.

Fig. 9 is an end view of the lower section of the stem shown in Fig. 8.

Fig. 10 is a vertical section through a stem of modified construction.

Referring to the drawing, the hollow bowl of the pipe is indicated at 1, this bowl being provided in the present case with the usual short shank 2 which has a comparatively large cylindrical socket 3 communicating with the chamber of the bowl through the small draft passage 4. The stem proper is constructed in two parts, an upper section 5, and a lower section 6. The upper section is provided at its outer end with a mouth piece 7 which is provided with a recess 8 at its inner end to receive a pin 9 which projects from the outer end of the lower section 6, the rear end of the section 6 abutting the shouldered portion of the mouth piece. The inner end of the upper section 5 is provided with a reduced portion 10, and the rear end of the lower section with a reduced portion 11, these reduced portions when placed together being of cylindrical form and adapted to snugly fit the socket of the shank 2 so as to firmly lock the two sections of the stem together.

The upper section 5 is provided with the usual draft passage 12, this draft passage extending from the inner end of a small metal tube 13, preferably placed in the inner end of the section 5, and entirely through the section to the outer end of the mouth piece 7.

The lower section 6 is hollowed out to provide a chamber 14 which is open at the top through the major portion of the length of the section 6, but is closed at each end by the walls 15 and 16. Leading from the draft passage 12 of the upper section 5 through the inner wall of said draft passage are a plurality of small openings 17, these openings communicating with the chamber 14 of the lower section and permitting all of the nicotine-laden moisture to drain from the draft passage into the chamber.

Referring more particularly to Fig. 4 it will be seen that the chamber 14 is of substantial width so that in the event the pipe is laid upon its side the moisture in the

chamber, flowing to one side of the chamber will be prevented from percolating back into the draft passage. To further insure against such possibility, I have provided the under 5 surface of the upper section 5 with a pair of channels 18, which extend the full length of the chamber and communicate therewith, these channels 18 receiving the moisture when the pipe is laid up-side-down are effectively obviating any danger of the moisture 10 returning to the draft passage.

In Fig. 10 there is shown a modification in which the division point between the upper section indicated at 5' and the lower section indicated at 6' is substantially on a line 15 with the draft passage 12' and the lower wall of the draft passage is enlarged and projects into the moisture-receiving chamber to provide a trap on either side thereof; this arrangement acting to prevent the 20 moisture from draining back into the draft passage when the pipe is in an abnormal position. Also, in this modified view there are shown ribs 19 on the lower section 6 which fit grooves 20 in the upper section 5 to make a tighter joint.

By this construction it will be seen that a very simple and effective arrangement is provided for draining the draft passage of 30 the pipe and for not only preventing the nicotine-laden moisture from re-entering the draft passage but also preventing the moisture from flowing to the socket of the shank, providing a dry smoke. It will also 35 be seen that when it is desired to clean the pipe this may be readily accomplished by removing the stem from the shank of the bowl and then readily separating the two sections of the stem by withdrawing the pin 9 from 40 the recess 8, the parts of the pipe being as readily re-assembled after cleaning.

Having thus described my invention, I claim:

1. In a smoker's pipe, a bowl, a stem, said 45 stem having an upper section and a lower section, a wall having a plurality of perforations dividing said sections, and means for removably securing said sections together, the upper section having a draft passage, the lower section having a chamber, said perforations constituting means for placing the draft passage in communication with the chamber when the sections are together; said chamber being otherwise closed 50 in the assembled condition of the parts.

2. In a smoker's pipe, a bowl, a stem, said 60 stem having an upper section and a lower section, a wall having a plurality of perforations dividing said sections, one of said sections having a mouth piece at its outer end, and means for movably securing said sections together, the upper section having a draft 65 passage, the lower section having a chamber, said perforations constituting means for placing the draft passage in communication

with the chamber when the sections are together, said chamber being otherwise closed in the assembled position of the parts.

3. In a smoker's pipe, a bowl having a socketed shank, a stem, said stem having an upper section and a lower section, a wall having a plurality of perforations dividing said sections, and means for removably securing said sections together, the upper section having a draft passage, the lower section having a chamber, said perforations constituting means for placing the draft passage in communication with the chamber when the sections are together, said chamber being otherwise closed in the assembled 70 condition of the parts and formed to provide a trap for the moisture therein.

4. In a smoker's pipe, a bowl having a socketed shank, a stem divided longitudinally into upper and lower sections, means 75 for removably connecting the outer ends of said sections together, the inner ends of said sections being insertable in the shank socket and held together thereby, said upper section having a draft passage, said lower section 80 having a chamber beneath said passage closed to the socket of the shank, and communicating means leading from said draft passage to said chamber.

5. In a smoker's pipe, a bowl having a socketed shank, a stem divided longitudinally into upper and lower sections, means 85 for removably connecting the outer ends of said sections together, the inner ends of said sections being insertable in the shank socket 90 and held together thereby, said upper section having a draft passage, said lower section having a chamber beneath said passage closed to the socket of the shank, and communicating means leading from said draft 95 passage to said chamber, said chamber being formed with a trap to prevent moisture therein from returning to the draft passage.

6. In a smoker's pipe, a bowl, a stem, said 100 stem having an upper section and a lower section, means for removably securing said sections together, the upper section having a draft passage, the lower section having a chamber, means for placing the draft passage in communication with the chamber 105 when the sections are together, said chamber being otherwise closed in the assembled condition of the parts, and the channel formed in the upper section on each side of the draft passage adapted to be placed in communication with said chamber when the parts are assembled.

7. In a smoker's pipe, a bowl, a stem, said 115 stem having an upper section and a lower section, a wall having a plurality of perforations dividing said sections, a mouth piece at the outer end of the upper section, and means for removably securing said sections together with the lower section abutting the mouth piece, the upper section having a 120

draft passage, the lower section having a chamber, said perforations constituting means for placing the draft passage in communication with the chamber when the sections are together, said chamber being otherwise closed in the assembled condition of the parts.

8. In a smoker's pipe, a bowl having a socketed shank, a stem having an upper section and a lower section, a mouthpiece at the outer end of one of said sections having a recess, a projection at the outer end of the other section adapted to enter said recess, the inner end of each section having reduced portions adapted to enter the socket of said shank, the upper section having a draft passage, the lower section having a chamber beneath said draft passage, a series of small passages leading from the draft passage to said chamber, said chamber being otherwise closed in the assembled position of the parts.

9. In a smoker's pipe, a bowl, a stem, said stem having an upper section and a lower section, means for removably securing said sections together, the upper section having a draft passage, the lower section having a chamber of greater width than the diameter of the draft passage, the lower wall of the draft passage projecting into said chamber so as to provide spaces on each side of said wall, said wall having openings to place the draft passage in communication with the chamber when the sections are together, said chamber being otherwise closed in the assembled condition of the parts.

In testimony whereof, I have hereunto set my hand this 18th day of February 1932.

GEORGE A. McCLAY.
